UNITED STATES PATENT OFFICE.

CHARLES L. McCUEN, OF DETROIT, MICHIGAN, ASSIGNOR TO PERFECTION ENGINEERING COMPANY, OF DETROIT, MICHIGAN, A CORPORATION OF MICHIGAN.

MANIFOLD CONSTRUCTION.

Application filed March 17, 1924. Serial No. 699,927.

The invention relates to manifold constructions of internal combustion engines and is particularly applicable to an eight-cylinder engine. The invention has for one of its objects the provision of an intake manifold for a multi-cylinder engine, the passages of which offer an equal resistance to the flow of the explosive mixture, whereby each cylinder receives an equal volume of the explosive mixture. Another object is the provision of an intake and exhaust manifold construction for respectively conducting equal volumes of explosive mixture to and receiving the exhaust gases from the cylinders and in which a wall of the intake manifold is heated by the exhaust manifold. With these as well as other objects in view, the invention resides in the novel features of construction and combinations and arrangements of parts as more fully herein-after set forth.

In the drawings:

Figure 1 is a side elevation of a manifold construction embodying my invention; 25 Figure 2 is a cross section on the line 2—2 of Figure 1 and showing, in addition, a portion of an internal combustion engine. 1 is the intake manifold having the parallel main passages 2 and 3, which are adapted to be connected to the discharge passages of a dual carburetor. 4 are oppositely extending inner intermediate passages connected at their adjacent ends to the main passage 2, and 5 are oppositely-extending outer intermediate passages connected at their adjacent ends to the main passage 3. These intermediate passages are separated by the common vertical wall 6. 7 and 8 are delivery passages leading from each of the inner and outer intermediate passages 4 and 5 respectively and adapted to communicate with the intake ports 9 of the multi-cylinder internal combustion engine 10. The delivery passages 7 are return-bent and extend 45 toward each other while the delivery passages 8 extend away from each other. Also, these delivery passages are all in the same vertical plane between the inner intermediate passages 4 and the engine 10. The cross sectional areas of the corresponding passages from the carburetor to the engine are equal and also the combined lengths of these passages are approximately equal, the combined lengths of the inner intermediate passages 55 and their respective delivery passages being

slightly less than the combined lengths of the outer intermediate passages and their respective delivery passages to compensate for the change in direction of the flow of the explosive mixture so that equal volumes of the explosive mixture flow from the carburetor to the engine cylinders.

For the purpose of heating any liquid fuel which drops from the explosive mixture while flowing through the intake manifold, I have provided the exhaust manifold 11 located preferably below the intake manifold 1 and preferably integral therewith, these manifolds being separated by the same horizontal wall 12 which forms the lower side of the intake manifold and the upper side of the exhaust manifold. The main passages 2 and 3 of the intake manifold extend vertically above the same and the carburetor is preferably located above this manifold also. With this arrangement, any liquid fuel which may drop from the explosive mixture while passing through the intake manifold comes into contact with the wall 12 which is heated throughout its entire extent by the passage of the combustion gases through the exhaust manifold. As a consequence this liquid fuel is vaporized, after which it again flows with the explosive mixture.

What I claim as my invention is:

1. In an intake manifold construction for internal combustion engines having a plurality of aligned cylinders, a plurality of main passages, a pair of oppositely-extending intermediate passages leading from each of said main passages, and a pair of oppositely-extending delivery passages leading from corresponding ends of the pair of said intermediate passages and adapted to communicate with the cylinders, each of said intermediate passages with its respective delivery passage offering the same resistance to flow of the explosive mixture therethrough.

2. In a manifold construction for an internal combustion engine, a pair of parallel main passages, oppositely-extending intermediate passages leading from each of said main passages, said intermediate passages extending in substantial parallelism to each other, delivery passages leading from the ends of corresponding intermediate passages and extending toward each other, and delivery passages leading from the ends of the other corresponding intermediate passages and extending away from each other,

the combined lengths of each of said first-mentioned intermediate passages and their respective delivery passages being sufficiently less than the combined lengths of each of 5 the other intermediate passages and their respective delivery passages to compensate for the change in direction of flow of the fluid therethrough.

3. In a manifold construction for an internal combustion engine, the combination 10 with a horizontally-extending exhaust manifold construction and an intake manifold construction extending adjacent to said exhaust manifold and having a wall adapted 15 to be heated by said exhaust manifold construction, said intake manifold construction having upwardly-extending main passages, a pair of oppositely-extending intermediate passages connecting into each of said main 20 passages, and oppositely-extending delivery passages at the corresponding ends of said intermediate passages adapted to communicate with the cylinders.

4. In a manifold construction for an internal combustion engine, the combination 25 with a horizontally-extending exhaust manifold construction and an intake manifold construction extending adjacent to said exhaust manifold and having its interior separated 30 from the interior of said exhaust manifold construction by a wall common to both, said intake manifold construction having a pair of upwardly-extending main passages, parallel intermediate passages extending in 35 opposite directions from each of said main passages, and oppositely-extending delivery passages leading from the same ends of said intermediate passages.

5. A manifold construction for an eight-cylinder internal combustion engine, the cylinders being in alignment, a carbureter, a pair of separate vertically extending main fuel conducting passages in direct communication with said carbureter, a pair of 40 intermediate parallel passages communicating directly with said main passages respectively, each of said intermediate passages having oppositely and outwardly extending portions, a pair of oppositely and outwardly 45 extending delivery passages directly communicating with corresponding ends of one of said intermediate passages, each of said delivery passages communicating with a pair of cylinders for supplying fuel there- 50 to, a second pair of oppositely and inwardly extending delivery passages directly communicating with corresponding ends of the other of said intermediate passages, each of the last said delivery passages communicat- 55 ing with other pairs of said cylinders, the cross sectional areas and lengths of the said intermediate passages and their respective delivery passages being arranged to conduct substantially equal volumes of the fuel from 60 the carbureter to the cylinders of the engine.

6. A manifold construction for an eight-cylinder combustion engine, the cylinders being in alignment, a carbureter, a pair of separate vertically extending main fuel conducting passages in direct communication with said carbureter, a pair of intermediate parallel passages communicating directly with said main passages respectively, each of 70 said intermediate passages having oppositely and outwardly extending portions, a pair of oppositely and outwardly extending delivery passages directly communicating with corresponding ends of one of said intermediate passages, each of said delivery 75 passages communicating with a pair of cylinders for supplying fuel thereto, a second pair of oppositely and inwardly extending delivery passages directly communicating with corresponding ends of the other of said intermediate 80 passages, each of the last said delivery passages communicating with other pairs of said cylinders, the cross sectional areas and lengths of the said intermediate 85 passages and their respective delivery 90 passages being arranged to conduct substantially equal volumes of the fuel from the carbureter to the cylinders of the engine, said intermediate and delivery passages lying in a common plane, and an exhaust passage formed in a plane parallel with 95 that aforesaid for conducting the exhaust gases from the engine cylinders into heat transfer relation to the said intermediate delivery passages.

7. A fuel mixture supplying device comprising in combination with an internal combustion engine having eight aligned cylinders; a pair of conduits; fuel mixture supply means for the conduits; one of said conduits extending from said fuel mixture supply means to supply fuel mixture to the third, fourth, fifth and sixth of said cylinders; the other of said conduits extending from said fuel mixture supply means to supply fuel mixture to the first, second, seventh and eighth of said cylinders; said conduits separately conducting the fuel mixture from the fuel mixture supply means to the respective cylinder groups aforesaid.

8. In combination with an internal combustion engine having eight aligned cylinders; a dual carburetor positioned substantially at the mid-point longitudinally of the engine cylinders; a pair of vertically extending manifold conduits separately communicating with the carburetor; a manifold passage extending generally longitudinally with respect to the engine cylinders and communicating with one of said vertically extending manifold conduits, opposite ends 115 of said manifold passage being arranged for respectively supplying fuel mixture to third, fourth and to the fifth, sixth, of said engine cylinders; a second manifold passage extending generally longitudinally with re- 120

spect to the engine cylinders and communicating with the other of said vertically extending manifold conduits, opposite ends of said second manifold passage being arranged for respectively supplying fuel mixture to the first, second, and to the seventh, eighth, of said engine cylinders, said manifold passages separately conducting fuel mixture from the respective manifold conduits to the respective cylinder groups 10 aforesaid.

In testimony whereof I affix my signature.

CHARLES L. McCUEN.
